UNITED STATES PATENT OFFICE.

MATTHEW W. ROBERTS, OF LUMBERTON, MISSISSIPPI.

COMMUTATOR-CLEANER.

1,382,547.

Specification of Letters Patent. Patented June 21, 1921.

Application filed March 28, 1921. Serial No. 456,367.

To all whom it may concern:

Be it known that I, MATTHEW W. ROBERTS, a citizen of the United States, residing at Lumberton, in the county of Lamar, State 5 of Mississippi, have invented certain new and useful Improvements in Commutator-Cleaners; and I do hereby declare the following to be a full, clear, and exact description of the invention, such as will enable 10 others skilled in the art to which it appertains to make and use the same.

This invention relates to new and useful improvements in cleaning devices and particularly to cleaning devices for the 15 commutators of electric motors.

One object of the invention is to provide a device adapted to hold a roll of felt, or other suitable soft material, against the face of the commutator of an electric motor, the 20 device being especially designed for attachment to the motors used in connection with electric railway signaling systems.

Another object is to provide a device of this character which is adapted to be supported on the threaded spindle of the motor 25 which holds the glass protective casing of the commutator, and maintained in proper position by the nut which holds the glass casing.

Other objects and advantages will be apparent from the following description when taken in connection with the accompanying 30 drawing.

In the drawing:

Figure 1 is a side elevation of a portion of a motor showing the invention applied thereto.

Fig. 2 is a top plan view of the same.

Fig. 3 is a perspective view of the cleaner 40 attachment removed from the motor.

Referring particularly to the accompanying drawing, 10 represents the commutator, 11 the brushes, 12 the threaded stem on which the glass casing 13 is engaged, and 14 45 the nut which is engaged on the stem to hold the casing in position.

The cleaner includes a suitable length of wire 15 having on one end a loop or eye 16, and having its other end straight. The loop or eye 16 is bent at right angles to the shank 50 of the wire and is slipped onto the threaded stem 12 and against the nut 17 which is engaged thereon. The shank of the wire extends horizontally inward and in parallel relation to and over the commutator 10, and 55 carried by this end is a roll 18 of felt or other suitable soft material, the wire being preferably of spring quality so as to press the felt against the outer face of the commutator, in advance of the brushes 11. 60 Thus, as the commutator rotates, the felt will wipe against the outer face thereof and keep the commutator free of foreign substances, as well as to keep the same free of practically all oil except the very minute 65 quantity required to lubricate the commutator and brushes.

By removing the wire and bending the same the required pressure of the felt, against the face of the commutator, can be 70 quickly obtained.

What is claimed is:

The combination with threaded stem of an electric motor which holds the protective casing of the commutator, and the nut there- 75 of, of a commutator cleaner comprising a wire shank disposed horizontally and longitudinally over the commutator and having on its outer end an angularly turned eye engaged on the said threaded stem, and 80 a roll of soft material carried by the other end of the shank and bearing against the face of the commutator, the shank being possessed of flexibility to maintain the soft material in contact with the commutator. 85

In testimony whereof I affix my signature in the presence of two witnesses.

MATTHEW W. ROBERTS.
